UNITED STATES PATENT OFFICE.

HARRY J. WHEELER, OF KANSAS CITY, MISSOURI.

MANIFOLD-HEATER FOR AUTOMOBILES.

1,388,538.

Specification of Letters Patent. Patented Aug. 23, 1921.

Application filed December 13, 1919. Serial No. 344,726.

To all whom it may concern:

Be it known that I, HARRY J. WHEELER, a citizen of the United States, residing at Kansas City, in the county of Jackson and State 5 of Missouri, have invented a new and useful Manifold-Heater for Automobiles, of which the following is a specification.

The invention relates to manifold heaters for automobiles, and the object of my invention is to provide a cheap heating device which may be readily attached on the automobile motor and heat the intake manifold to effect a prompt starting of the motor in cold and freezing temperatures.

I attain this object by means of the construction and combination of parts illustrated in the accompanying drawing in which—Figure 1, is a side elevation of the front portion of an automobile, partly 10 broken away to disclose the intake and exhaust manifolds, and showing my invention in place to heat the former; Fig. 2, is a top plan view of a heating device constructed in accordance with my invention; Fig. 3, is a 15 cross section of the same, on the line 3—3, in Fig. 2; Fig. 4, is a plan view of the burner jacket, and Fig. 5, is a plan view of the asbestos filler for the burner.

Similar numerals of reference refer to corresponding parts throughout the several views.

The numeral 1, designates the hood covering of the motor 2, which is provided with the customary intake manifold 3, and exhaust manifold 4, which are secured on the motor by clamps 5. The manifold heater 6, comprises a metal trough-shaped member 7, on the outer end of which is formed a bay 8, adapted for receiving fuel, such as oil, 20 gasoline, paraffin, and like combustible substances and a substantially L-shaped flat arm 9, integral with the inner end of the member, the foot portion of the arm being off set a suitable distance from the body of the member, so that the member may be held at a distance from the vertical portion of the arm. A burner member 10, which consists of a suitable pad of non-combustible material 11, preferably asbestos fabric which is rolled 25 to form a cylindrical body and then wrapped around by a metal jacket 12, having a plu-

rality of perforated apertures 13, is lodged in the member 7, and extending a little distance in the bay 8, therein.

The heating device is attached on the motor by imposing the upper end of the arm 9, between the manifold clamp 5, and the adjacent manifold and in such a manner that the trough of the member 7, shall be positioned directly under the intake manifold. The 55 burner member is then lodged in the member 7, and fuel placed in the bay 8, from whence it flows into the trough proper and partially submerging the burner member, the latter being formed to have a diameter large enough 60 to allow one third, approximately, thereof to rise above the trough of the member 7. In cold and freezing temperatures, it is my experience, the motor seldom can be started 65 promptly, because the cold has chilled the 70 parts, particularly the manifolds, and consequently the gasoline evaporation and expansion is greatly retarded. To warm and heat the intake manifold the operator simply places a quantity of fuel in the heater, lights 75 the same, and the flame produced strikes against the intake manifold and adjacent parts of the motor and, in a few seconds of time, gas is generated and the motor starts. The liquid fuel invades the asbestos filler of 80 the burner member and is ignited and burns at the perforations in the jacket thereof, thereby effecting a uniform heating of the 85 manifold.

Having described my invention what I claim is—

A manifold heater for automobiles, consisting of an open trough-shaped liquid fuel receptacle having an end basin and a vertically extending arm adapted for attaching 90 on the manifold, and a portable burner member lodged in the trough of said receptacle and extending into the basin therein, said burner member comprising a rolled pad of non-combustible material which is rolled in 95 a perforated sheet of metal to form a wick.

Kansas City, Missouri, December 6th, 1919.

HARRY J. WHEELER.
